UNITED STATES PATENT OFFICE.

BENJAMIN MERIAM, OF BOSTON, MASSACHUSETTS.

DRAIN-TESTING APPARATUS.

SPECIFICATION forming part of Letters Patent No. 417,210, dated December 10, 1889.

Application filed January 25, 1888. Serial No. 261,923. (No model.)

To all whom it may concern:

Be it known that I, BENJAMIN MERIAM, a citizen of the United States, residing at the city of Boston, in the county of Suffolk and State of Massachusetts, have invented a new and useful Drain-Testing Apparatus, of which the following is a specification.

The nature of my invention is that of a pipe or other vessel prepared to be connected, 10 by means of a screw or otherwise, with the bore of the drainage or foul-water pipe or with the sewer used in houses, &c., the said pipe being provided near its top with an inside flange or other support, which carries a 15 detachable and removable vessel or cup of peculiar construction, in which cup rests a glass or other frangible vessel containing an odorous substance, which substance is liberated to the surrounding air within the pipe 20 by a device for breaking the vessel or a portion of it; and the object is to provide a cheap and easily-managed device for effecting detection of the location of breakages in the drain-pipe or the sewer which the drain-pipe 25 enters by means of the escape of odors from the contents of the cup above mentioned.

In the drawings, Figure 1 is a drawing in vertical cross-section of one form of my device. Fig. 2 is a top view of the same. Figs. 30 3, 5, 6, and 7 are drawings in horizontal cross-section in lines shown in Fig. 1, as herein-after noted. Fig. 4 is a view hereinafter explained.

In the drawings, F F, Fig. 1, is a short pipe, 35 preferably of brass, (not necessarily of a pipe form, and sometimes bearing a pipe screwed to its bottom,) bearing at its top, screwed on, (and thus removable,) a cap G G, Fig. 1, also of brass, (or other metal possibly.) Between 40 the upper end of the pipe F F and the cap G G is a washer H H, Fig. 1, of leather, cork, or other appropriate substance. Firmly attached to (cast on the top of) the cap G G is a boss J, presenting (see Fig. 2) in top view 45 the form of a hexagonally-shaped nut. In the center, inside of the cap G G, (in the lower surface of its horizontal portion,) is a dent or cavity. (See Fig. 1.) Into this cavity enters the cone-shaped top of a rod or bar K, called 50 the "discharging-rod." This rod K passes

through a hole in the center of a "spider" L L, Fig. 1, or plate with apertures presented concentrically, (see Fig. 3,) which spider is screwed concentrically in and across the upper part of the pipe F F. (See Fig. 3.) The rod 55 K proceeds perpendicularly downward, and bears at its lower end a plate M, with projections on its lower surface, (see Figs. 1 and 4,) which plate is called the "crusher." Beneath this crusher (see Fig. 1) is the glass 60 bottle N, lying on its side, tightly corked and nearly filled with, preferably, oil of peppermint. I sometimes fill this bottle with ether, or any other volatilizable liquid or solid—such as camphor or ambergris—which is odorous, and sometimes, instead of a glass or pottery-ware bottle, I use a vessel of any eligible substance, providing it at its top side with a pane or button, of glass or any other easily-frangible substance. This bottle N rests in 70 a vessel P P, Fig. 1, called the "odor-tank," which is in the shape of a short hollow cylinder open at the top, but bearing a bottom, and carrying projecting from its upper edge two rods or bars Q Q, Fig. 1, to draw it up 75 with and return it, which rods extend upward to a point just beneath the spider L L, and are at their respective tops bent to a right angle and proceed a short distance horizontally toward the axial center of the 80 pipe F F, to answer as a handle. (See Fig. 1.) This odor-tank P P rests on an inner flange attached to the bottom of the pipe F F, and its bottom is formed with a cup-shaped curvature at the center Z, (seen in Fig. 1,) while 85 round its outer portion (see Fig. 7) the bottom bears eight (more or less) apertures passing through it. At its bottom the pipe F F is fastened to a branch pipe R, Fig. 1, proceeding from the soil or drain pipe S, Fig. 1. When 90 the soil or drain pipe is horizontal, or nearly so, at the point where my device is attached, I sometimes dispense with the branch pipe R and utilize instead thereof the lower end of the pipe or vessel F F, (perhaps lengthened for that purpose,) this lower end thus becoming virtually the branch pipe a, which I consider it in my claims as herewith defined.

Operation: The spider L being unscrewed, 100

and with the rod K and the crusher M withdrawn from the pipe F F, then by means of the rods Q Q the cup P P is drawn up out of the pipe F F, and the bottle N, filled with oil 5 of peppermint or other volatilizable odorous substance, is placed therein, having first been tightly corked. The cup being then returned to the pipe, the spider, rod, and crusher are also returned, and the king-screw on the 10 end of the pipe F F is well greased—say with tallow—and the cap G G is screwed nearly down (which screwing is much facilitated by the nut J) to such a point as that the crusher M rests lightly on the glass bottle N, as seen in 15 Fig. 1. The pipe F F now bears its contents hermetically sealed in, (as to the upper part of the pipe,) and is carefully taken and either fastened at once onto the drain-pipe or it is laid aside until its use is needed.

20 I do not limit myself to any special means of connection of my device with the drain-pipe. Sometimes I screw it into the opening used to draw foul water from a bath-tub. Sometimes I attach the pipe to a water-closet fixture, 25 or to the drain-pipe of a sink, or I place it independently by itself and connect it with an aperture made in any conveniently-accessible portion of the drain-pipe, as seen in Fig. 1.

30 The device may be connected with the drain-pipe anywhere between the main sewer and the pipe at the top of the house, and with any and every part of the drain-pipe, as may be desired; and I sometimes, when the ramifications of the drain-pipe are quite extensive, use two or more of the test-pipes. In 35 all well-constructed drains a stench-trap, a well-known device, is used, and is usually attached to the drain or the sewer outside of the house. The duct may leak and discharge foul air either on the hither or farther side of the trap, and I apply my test-pipe accordingly, according to judgment or supposition as to the locality of the leakage.

40 In the practical use of my invention we will suppose that the air in the duly piped and drained house becomes permeated with foul odors. The drain-pipes running from various rooms down to the sewer are concealed 45 behind the plastering or the floor-boards. The portion of the draining devices in the cellar is hidden, say, by a brick floor. To open at random the wall or a floor to discover an aperture perhaps not more than an eighth 50 of an inch in diameter (a hole gnawed by a rat in a lead pipe) or a crack an inch or two long and opening one-sixteenth of an inch, (say in an earthen pipe broken by a sunken beam or a loose joint in an iron pipe,) and 55 the presence of either of these defects is enough to taint a house so as to render it unhealthy and uninhabitable, to explore at random would be costly, as many successive attempts might all be inefficacious; but a 60 strong distinctive odor being liberated in-

side the closed pipe above, it will of course emerge at any point of breakage in the pipe. This is the foundation of the plan upon which in or about the year 1874 I proceeded in suggesting the adoption of the now widely-⁷⁰ adopted practice (which I never patented) of testing drain-pipes, drains, and sewers, as to their integrity of condition, by means of the use of odors.

To use my invention, if this apparatus is not already connected with the drain-pipes, this connection is effected. The cap G G is forcibly screwed down, which causes the crusher M to break the bottle N. (Sometimes I cause the crusher M to force in a stopper instead of breaking a vessel.) The peppermint-oil or other contained substance (being odorous) is exposed to the air in the drain-pipe. If a liquid is used, a portion of it runs down into the cup portion of the vessel P P, Fig. 1. The rest runs through the apertures (seen in Fig. 7) of the other part of the vessel-bottom and down the pipe. The liquid or gas (if ether is used) or the gaseous product of the volatilization of the solid substance contained in the vessel N passes into the pipe, and wherever there may be a breakage, leak, or solution of continuity in the pipe or the sewer, the odor emerges, and the experimenter is fully apprised by his olfactory organs of the exact location of the breakage, as the odor is of course strongest where the odorous gas or vapor first emerges, unmixed, as it then is, with much atmospheric air. The portion of liquid remaining in the cup of the vessel P P stays there till evaporated, and is till then a source of supply of the desired odor, and is a permanent test as long as it remains there. The place of the leakage being thus detected, it is at once reached, the breakage or defect repaired, the device, subject to this application, is again charged, as hereinabove described, and is then left undisturbed till a similar exigency again requires its use.

I do not claim any device or combination of devices for the forcible propulsion of atmospheric air into or in contact with the body of odorous substance; nor do I claim any device for the liberation of chemicals to be combined with other substances in the main containing vessel and fitted for the extinguishing of fires.

I claim—

1. In the apparatus hereinabove described for the detection of the location of flaws in drain-pipes, sewers, and other containing vessels by the use of odorous substances, the combination of the containing pipe F F and its removable cover G G, with the discharging-rod K, the frangible odor-containing vessel N, and the branch pipe R, all constructed and arranged substantially as shown and described.

2. The combination and arrangement of

the pipe F F and its cover, and the rod K and vessel N, with the odor-tank P P and branch pipe R, all constructed and arranged substantially as shown and described.

5 3. The combination and arrangement of the pipe F F and its cover, and the rod K and vessel N, with the odor-tank P P, and

the placing rods or bars Q Q and branch pipe R, all constructed and arranged substantially as shown and described.

BENJAMIN MERIAM.
